UNITED STATES PATENT OFFICE.

THADDEUS S. COFFIN, OF REVERE, MASSACHUSETTS.

SHOW-TRAY.

SPECIFICATION forming part of Letters Patent No. 690,399, dated January 7, 1902.

Application filed March 30, 1901. Serial No. 53,627. (No model.)

To all whom it may concern:

Be it known that I, THADDEUS S. COFFIN, a citizen of the United States, residing at Revere, in the county of Suffolk and State of Massachusetts, have invented certain new and useful Improvements in Show-Trays; and I do hereby declare the following to be a full, clear, and exact description of the invention, such as will enable others skilled in the art 10 to which it appertains to make and use the same.

This invention relates to show-trays for rings, watches, and other similar articles; and it consists in the novel construction and 15 combination of the parts hereinafter fully described and claimed.

In the drawings, Figure 1 is a plan view of a show-tray embodying this invention. Fig. 2 is a cross-section through the show-tray, 20 taken on line xx in Fig. 1. Fig. 3 is a section taken on line yy in Fig. 1. Fig. 4 is an end view of the top part of the rack.

A is the outer portion of the tray, which has raised sides a' . B is a rack arranged in the tray and provided with a facing-plate b of celluloid or other similar ornamental material. The rack 25 consists of parallel bars held in position by cross-pieces c and having beveled edges c' on their under sides.

D represents spring-loops of celluloid or other similar material secured to the under sides of the parallel bars and projecting at the front of the rack through narrow slits b' in 30 the facing-plate.

E represents wedge-plates secured between the bars and pressing the spring-loops against the beveled edges c' . The beveled edges c' determine the angle of inclination of the spring-loops, and the spring-loops are arranged opposite each other in pairs. The articles to be exhibited are held between the pairs of spring-loops.

In the upper part of Fig. 1 loops D' are shown, which are spaced farther apart than the loops D , so as to hold watches. The loops D' are secured to the rack in the same manner as the loops D ; but the wedge-shaped plates E' , which hold them in position, are square instead of being oblong, like the plates E . Plates c' are also used to hold the wedge-shaped plates E in position; but any approved means may be used for securing either form of wedge-plate E or E' .

What I claim is—

The combination, with a rack provided with bars having beveled edges, and a facing-plate having slits in it; of inclined spring-loops secured to the bars in pairs and projecting through the said slits, and wedge- 55 plates holding the said loops against the said beveled edges, substantially as set forth.

In testimony whereof I affix my signature in presence of two witnesses.

THADDEUS S. COFFIN.
